A. M. KRUSE,

CONTAINER,

APPLICATION FILED JUNE 4, 1921.

1,400,685.

Patented Dec. 20, 1921.

INVENTOR

August M. Kruse,
By Lynn L. Crampton,
Atty.

UNITED STATES PATENT OFFICE.

AUGUST M. KRUSE, OF DEFiance, OHIO.

CONTAINER.

1,400,685.

Specification of Letters Patent. Patented Dec. 20, 1921.

Application filed June 4, 1921. Serial No. 474,883.

To all whom it may concern:

Be it known that I, AUGUST M. KRUSE, a citizen of the United States, and a resident of Defiance, in the county of Defiance and State of Ohio, have made an Invention Appertaining to Containers; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to containers and particularly to those of the metallic type intended for the handling and shipment of milk.

20 In the shipment and handling of milk it is not only important to have a container which is strong and durable in its construction to withstand the hard usage to which subjected, but also to have the container devoid of cracks, crevices or sharp angles which are difficult to clean and wherein filth and bacteria accumulate.

25 The primary object of the invention is the provision of a strong, durable and reinforced metallic container of the character described, which, while composed of a plurality of assembled parts, is free from cracks, shoulders and crevices for the accumulation of bacteria.

30 A further object of the invention is the provision of a simple and inexpensive reinforced breast construction for containers of the class described, whereby to enhance the practicability and commercial value thereof.

35 The invention is fully described in the following specification, and while, in its broader aspect, it is capable of embodiment in numerous forms, a preferred embodiment thereof is illustrated in the accompanying drawings, in which,—

40 Figure 1 is a side elevation of a container embodying the invention with parts broken away. Fig. 2 is a fragmentary detail of the joint between the body and breast member of the container with the parts in separated relation, and Fig. 3 is a similar view of the joint between the container body and bottom members and reinforcing means with the parts in separated relation.

45 Referring to the drawings, the container embodying the invention is entirely of metal and has a cylindrical body member 1, a top

or breast member 2, and a bottom member 3. The breast member 2 is provided with the customary top opening 4 which is closed by a removable cover 5. The breast and body members 2 and 3 are preferably stamped from sheet metal and the body member is preferably formed from sheet metal rolled into cylindrical shape with the meeting end edges thereof butt-welded, as at 6, to provide an integral joint therebetween.

The body member 1 is straight throughout its length and at its upper end telescopes or fits closely within an offset portion 7 at the lower edge of the breast member 2, the extent of the offset of the portion 7 corresponding to the thickness of the body material so that the inner surface of the body member will be flush with and form a continuation of the inner surface of the breast member. The body and bottom members 1 and 3 are interengaged in the same manner, the bottom member having its top edge annularly offset as shown at 8 to telescopically receive the lower edge of the body member 20 with the inner surface of one flush with the inner surface of the other. Upon the assembling of either the breast or bottom member with the container body the two are integrally united by welding so that a close 85 integral joint is provided therebetween, thereby closing any seam or crevice which might otherwise be present between the body member and the respective breast or bottom member. While the welding may be accomplished in any desired or suitable manner, in practice oxy-acetylene welding is employed.

When the joints between the body member 1 and the breast and bottom members 2 and 3 have been made by welding or otherwise, the container is reinforced and strengthened by the mounting of a top reinforcing band 9 and a bottom reinforcing band 10 on the container, the latter band extending below the container bottom and serving as an annular supporting base for the container. The band 9 preferably, but not necessarily, has its outer surface of arcuate form in cross-section and is provided entirely around its inner side with a recess 105 11 for receiving the offset portion 7 of the top member 2. This band has its ends butt welded and is preferably shrunk on the container.

The bottom band 10 is internally provided near its upper edge with an annular groove 13 for receiving the offset portion 8 of the

bottom member 3, the band extending a distance below the bottom to provide a supporting base therefor. This band is secured in position on the container in the same manner as the band 9.

The top portion of the breast member 2 is reinforced by an external incasing member 14, which has a skirt portion extending down a distance over the breast portion of the top member, and has a waist portion embracing and reinforcing the cylindrical neck portion 15 forming the opening 4 of the top member. These parts are preferably welded together at points to rigidly unite the same and the upper edge of the neck portion 15 is turned outward and downward around the outer free end of the waist portion of the member 14. This gives the breast and neck portion of the container a very rigid and durable construction.

It is evident that I have provided a metallic container for milk or the like which is exceedingly strong and durable in its construction, has the top and bottom members thereof joined to the body member in substantially end abutting relation with their inner surfaces in alinement and integrally connected by welding so as to avoid any cracks or crevices therebetween in which dirt and bacteria might accumulate.

I wish it understood that my invention is not limited to any specific construction, arrangement, or form of the parts, as it is capable of numerous modifications and changes without departing from the spirit of the claims.

Having thus described my invention, what I claim as new and desire to secure by Letters Patent, is,—

40. 1. A container of the class described having a cylindrical body member, a bottom member having an annularly offset edge por-

tion for telescopically receiving the bottom edge of the body member, the members being rigidly secured one to the other at the joint therebetween, a reinforced bottom band closely embracing the offset portion of the bottom member and having an internal recess receiving the same, said bottom band extending below the bottom member to form a 45 50 base support for the container.

2. A container of the class described having a cylindrical body member, a top member and a bottom member, each having an annularly offset inner edge portion for telescopically receiving the respective edge of the body member with the inner surfaces of the top and bottom members flush with the inner surface of the body member, the joints between the members being integral as by 55 welding, a reinforcing band closely embracing the offset portion of the top member and having an internal recess receiving the same, and a bottom band closely embracing the offset portion of the bottom member and 60 65 having an internal recess receiving the same, said bottom band extending below the bottom member to form a base support for the container.

3. A container of the class described having a breast portion terminating at its upper end in a cylindrical neck forming an opening, a sheet metal reinforcing member having a skirt portion fitting over and down a distance on the breast member in protecting 75 relation thereto and having a waist portion closely encircling the neck portion of the breast member, the upper end of the neck extending outward and downward in close embracing relation to the upper end of the 80 reinforcing member.

In testimony whereof I have hereunto subscribed my name to this specification.

AUGUST M. KRUSE.
